[57] CLAIM

The ornamental design for a cup baffle, as shown and described.

DESCRIPTION

FIG. 1 is a perspective view of the drinking cup baffle showing my new design;

FIG. 2 is a top view thereof;

FIG. 3 is a side elevational view thereof;

FIG. 4 is a bottom view thereof;

FIG. 5 is a cross-sectional view thereof shown positioned on the vacuum bottle; and,

FIG. 6 is a cross-sectional view thereof shown in the cup.

The vacuum bottle and cup are shown in broken lines for illustrative purposes only.
